Primary Examiner — Jennifer Rivard*Assistant Examiner* — Alison M Ofstun(74) *Attorney, Agent, or Firm* — Thorpe North & Western LLP(57) **CLAIM**

The ornamental design for a rechargeable keychain light, as shown and described.

DESCRIPTION

FIG. 1 is a top perspective view of a rechargeable keychain light, showing our new design;

FIG. 2 is a front view of FIG. 1;

FIG. 3 is a back view of FIG. 1;

FIG. 4 is a side view of FIG. 1;

FIG. 5 is an opposite view of FIG. 4;

FIG. 6 is a top view of FIG. 1; and,

FIG. 7 is a bottom view of FIG. 1.

In the drawings, the broken lines represent portions of the article which form no part of the claimed design.

1 Claim, 5 Drawing Sheets(56)
